UNITED STATES PATENT OFFICE

117,564

DESIGN FOR AN OZONIZER

Siegfried Held, Chicago, Ill.

Application August 4, 1938, Serial No. 79,085

Term of patent 7 years

To all whom it may concern:

Be it known that I, Siegfried Held, a citizen of the United States, residing at Chicago, Cook County, Illinois, have invented a new, original, and ornamental Design for an Ozonizer, of which the following is a specification.

The design is shown in the accompanying drawing, which form a part thereof, and in which:

I claim:

The ornamental design for an ozonizer, substantially as shown.

SIEGFRIED HELD.
